James A. Hinson Inventor

By W. A. Edmunds Attorney

UNITED STATES PATENT OFFICE.

JAMES A. HINSON, OF CHICAGO, ILLINOIS.

HEAD-BLOCK FOR RAILWAY-CARS.

SPECIFICATION forming part of Letters Patent No. 635,322, dated October 24, 1899.

Application filed February 3, 1899. Serial No. 704,375. (No model.)

To all whom it may concern:

Be it known that I, JAMES A. HINSON, a citizen of the United States, residing at Chicago, in the county of Cook and State of Illinois, 5 have invented certain new and useful Improvements in Head-Blocks for Railway-Cars; and I do declare the following to be a full, clear, and exact description of the invention, such as will enable others skilled in the art to

10 which it appertains to make and use the same.

This invention relates generally to railway-cars, and particularly to buffering devices therefor; and it has for its object to provide a simple, durable, and effective buffering device and head-block adapted to relieve the cars of the injurious effects from the violent shocks to 15 which they are subjected when in use; and it consists of the parts and combinations of parts hereinafter described and claimed.

20 In the accompanying drawings, forming a part of this specification, Figure 1 is a plan view of my invention; Fig. 2, a vertical transverse section on the line $y-y$, Fig. 1; Fig. 3, a vertical section on the line $x-x$, Fig. 1; and 25 Fig. 4, a detail perspective view of the buffering-head.

Similar letters refer to similar parts throughout all the views.

Referring to the drawings, A represents the 30 end sill of a railway-car, and B a car-coupler of the Janney type. The coupler may be provided with any desired or preferred form of knuckle and locking device, and it may be connected with any preferred form of draft-rigging and work equally well with my hereinafter-described buffering device. The draw-head, however, is cast or otherwise provided with a vertical flange a , adapted, when the 35 coupler is drawn back, to engage the buffering-head C, mounted in the head-block D. The head-block D is preferably formed of metal and secured to the end sill by means of bolts b and rests on and is secured to the draft-sills E by vertical bolts c , which also serve to secure the bar F and the strap-iron G, which 40 carry the free end of the draw-bar, to the head-block and draft-sills. The strap-iron G is carried up and bolted to ears or lugs d , formed on the ends of the head-block. The 45 head-block D is formed with the cylindrical

pockets e to receive the buffering-springs H, against which the buffering-head C bears. The inner or adjacent walls f of the pockets e do not extend to the outer surface or face of the head-block, but terminate in rear of the same 55 in order to provide the necessary space for the play of the buffering-head, the stem g of which enters the slot or opening n between said walls f and extends into a recess (shown in dotted lines, Fig. 1) formed in the head-block, in which position it is secured by means of a bolt or pin L, inserted through an opening in the head-block and passing through an elongated opening h in the stem g of the buffering-head. The bolt or pin L is secured in 60 position by means of a key i, passed through said pin or bolt. The buffering-head C fits easily at all points in the openings to the pockets e and engages the springs therein to relieve the car to which it is attached, as well as those 65 which may be brought into violent contact with it, of the injurious effects of violent buffering whether the cars operating against it be supplied with buffering devices or are not so supplied. The draft-sills E are shown as 70 made of channel-iron and provided with a wood filling; but the latter is not absolutely necessary and may be left out.

Having thus described my invention, what I claim as new, and desire to secure by Letters 75 Patent, is—

1. A head-block for railway-cars having adjacent pockets formed therein, springs arranged in said pockets, and a buffering-head secured intermediate of said pockets in said 80 head-block and adapted to engage said springs.

2. A head-block for railway-cars having pockets formed therein and a slot or opening intermediate said pockets, springs arranged 85 in said pockets, an elongated buffering-head having a central stem adapted for insertion in said slot, and means for limiting the movement of said buffering-head.

In testimony whereof I affix my signature 90 in presence of two witnesses.

JAMES A. HINSON.

Witnesses:

JAS. H. ZEARING,
CECIL TH. FARMER.
